UNITED STATES PATENT OFFICE

VINTON E. SISSON, OF CHICAGO, ILLINOIS, ASSIGNOR TO WALTER P. MURPHY, OF CHICAGO, ILLINOIS.

DROP-END GONDOLA CAR.

1,260,468.

Specification of Letters Patent. Patented Mar. 26, 1918.

Application filed June 19, 1916. Serial No. 104,380.

To all whom it may concern:

Be it known that I, VINTON E. SISSON, a citizen of the United States, residing at Chicago, in the county of Cook and State of Illinois, have invented certain new and useful Improvements in Drop-End Gondola Cars, of which the following is a specification.

My invention relates to a drop end gondola car. These cars are frequently used for carrying structures such as steel girders, rails, and the like, which are longer than the car, and in such case the end gates, which are, of course, supported in upright position when the car is used for bulk freight, lie flatwise on the floor under the girders, rails, or the like. For this reason, and because of the hard usage which the gates receive in being opened and closed, and also while the car is in transit, due to cargo thrusts when the car happens to be loaded with heavy, movable articles, the gates are likely to be injured so that as heretofore constructed, they have required repair and replacement very frequently.

The principal object of my invention is to provide an end gate for a drop end gondola car which will be capable of withstanding the heavy stresses and rough usage to which this part of the car is subjected when in service.

The invention consists in the novel constructions, arrangements and devices in the end gates of drop end gondola cars to be hereinafter described and claimed.

The invention is illustrated, in certain preferred embodiments, in the accompanying drawings wherein—

Figure 1 is an end view of the superstructure of a drop end gondola car constructed in accordance with my invention.

Fig. 2 is a sectional plan taken on line 2—2 of Fig. 1.

Fig. 3 is a fragmentary side elevation of the car.

Fig. 4 is a sectional view taken on line 4—4 of Fig. 1, showing the end gate in upright position.

Fig. 5 is a similar view showing the end gate lying on the flooring of the car.

Fig. 5^a is a fragmentary plan view illustrating the means of connecting the end gate to the underframing of the car, said view illustrating in plan the position of the connecting elements illustrated in Fig. 5.

Fig. 6 is a detail sectional view, on a larger scale than the preceding figures, showing the construction of one of the hinges employed for hinging the gate to the body of the car.

Fig. 7 is a fragmentary inside end elevation of one of the upper corners of the gate.

Like characters of reference designate like parts in the several figures of the drawings.

Referring to the drawings, 10 designates the under frame of the car, 11, 11 the side walls and 12 the flooring. 13 is an angular pressed steel member secured to the under frame of the car and formed with an upstanding flange 14, the function of which is to form a stop strip for the end gate when the latter is in upright position. The end gate consists preferably of a sheet of metal 15 formed with corrugations 16 which preferably run horizontally of the sheet, merge into each other and terminate within the edges of the sheet. These corrugations are preferably pressed so that they extend inwardly of the car from the plane of the flat portions of the sheet. The edges of the sheet are preferably provided at the side with stiffening flanges 17, 17, at the top with a flange 18, and at the bottom with a flange 19 which flanges, if formed integral with the body of the sheet, as shown, are joined one with another by angle pieces 20.

The upper edge of the gate is further reinforced by an angle bar 21. Each of the side walls 11 is provided with a pair of angle strips 22, 23 having overlapping flanges projecting into the end opening against which the end gate lies when in upright position.

The gate is hinged to the body of the car by any suitable number of hinges of such character as to permit the gate to be folded down upon the floor of the car as shown in Fig. 5. I have shown these hinges consisting, in each case, of a U-bolt or staple 24 on the upstanding flange 14 of the angle bar 13, a U-bolt or staple 25 on the lower flange 19 of the gate, and a loop or ring 26 connecting the bolts. The gate is held in upright position by means of latch bars 27 loosely connected with the gate by staples 28, and brackets 29 on the ends of the side walls of the car, the latch bars being preferably constructed with their free extremities in the form of hooks 30 which extend around the brackets.

It will be seen that the end gate consists

of a very strong and rigid structure which is in the shape of a shallow box stiffened, that is to say, a corrugated panel reinforced by a rigid circumferential, angularly disposed flange. The corrugations of the panel add materially to its strength and rigidity. When the gate is folded down it is supported on the floor by flanges 17, 18, 19, the flange 18 at the upper end of the gate being strengthened by means of an angle bar 21. The structure is, therefore, capable of carrying very heavy loads without being crushed or bent.

I claim:

- 15 1. In a drop end gondola car, the combination with the body of the car, of an end gate comprising a sheet of metal formed with a plurality of contiguously arranged corrugations which terminate within the edges of the sheet, means for hinging said end gate at its lower edge to said car body, and means engaging the edges of said gate adjacent the ends of said corrugations when said gate is in its end-closing position.
- 25 2. In a drop end gondola car, the combination with the body of the car, of an end gate comprising a sheet of metal formed with a plurality of contiguously arranged corrugations which terminate within the edges of the sheet and provided with stiffening flanges angularly disposed with respect to the body of the sheet, means for hinging said end gate at its lower edge to the car body, and means on the body of the car 35 against which the bottom and vertical edges of the gate bear when the gate is in closed position.
- 35 3. In a drop end gondola car, the combination with the body of the car, of an end gate comprising a sheet of metal formed with a plurality of contiguously arranged corrugations which terminate within the edges of the sheet and provided with stiffening flanges angularly disposed with respect to the body of the sheet and projecting inwardly of the car so that when folded down said flanges rest upon the floor of the car, and means for hinging said end gate at its lower edge to the car body.
- 50 4. In a drop end gondola car, the combination with the body of the car, of an end gate comprising a sheet of metal formed with a plurality of contiguously arranged corrugations which terminate within the edges of the sheet and formed with integral angularly disposed stiffening flanges, angle members for joining said flanges one with another, means for hinging said end gate at its lower edge to the car body, and means on the body of the car against which the bottom and vertical edges of the gate bear when the gate is in closed position.
- 55 5. In a drop end gondola car, the combination with the body of the car, of a sheet metal end gate consisting of a sheet metal

end panel having its edges bent at right angles to the plane of the sheet to provide an inwardly projecting rigidifying rim, means for hinging said end gate at its lower edge to the car body, and means on the body of the car against which the bottom and vertical edges of the gate bear when the gate is in closed position.

6. In a drop end gondola car, the combination with the body of the car, of a sheet metal end gate consisting of a sheet metal end panel formed with stiffening corrugations and having its edges bent at right angles to the plane of the sheet to provide an inwardly projecting rigidifying rim, means for hinging said end gate at its lower edge to the car body, and means on the body of the car against which the bottom and vertical edges of the gate bear when the gate is in closed position.

7. In a drop end gondola car, the combination with the under frame and side walls of the car, of means constituting inwardly projecting flanges on the extremities of said side walls, an upwardly projecting flange on the under frame in the same plane with the aforementioned flanges, and a corrugated sheet metal end gate hinged at its lower edge to the car and adapted to bear against said flanges when in upright position.

8. In a drop end gondola car, the combination with the under frame and side walls of the car, of means constituting inwardly projecting flanges on the extremities of said side walls, an upwardly projecting flange on the under frame in the same plane with the aforementioned flanges, and a corrugated sheet metal end gate hinged at its lower edge to the car and adapted to bear against said flanges when in upright position, said end gate being provided with a continuous, rigid, inwardly projecting marginal flange on which the gate is supported when folded down on the floor of the car.

9. In a drop end gondola car, the combination with the under frame, sides and flooring of the car, of an angular member secured to said under frame having an upstanding flange spaced from the flooring of the car, and an end gate hinged at its lower edge to said upstanding flange consisting of a sheet metal panel provided with a rigidifying rim angularly disposed with respect to the body of the sheet and projecting toward the interior of the car.

10. In a drop end gondola car, the combination with the under frame, sides and flooring of the car, of an angular member secured to said under frame having an upstanding flange spaced from the flooring of the car, an end gate hinged at its lower edge to said upstanding flange consisting of a sheet metal panel provided with rigidifying flanges angularly disposed with respect to the body of the panel and projecting toward the interior

of the car, a pair of angle strips attached to the inside and outside, respectively, of each of said side walls with overlapping flanges projecting into the end opening against which said end gate bears when in upright position.

11. In a drop end gondola car, the combination with the under frame, sides and flooring of the car, of an angular member secured to said under frame having an upstanding flange spaced from the flooring of the car, an end gate hinged at its lower edge to said upstanding flange consisting of a sheet metal panel provided with rigidifying flanges angularly disposed with respect to the body of the panel and projecting toward the interior of the car, a pair of angle strips attached to the inside and outside, respectively, of each of said side walls with overlapping flanges projecting into the end opening against which said end gate bears when in upright position, latch bars on said end gate having hook forming extremities, and brackets on the car adapted to be engaged by said latch bars.

12. In a drop end gondola car, the combination with the body of the car, of a sheet metal end gate hinged at its lower edge to the body of the car and consisting of a sheet metal panel formed with a plurality of inwardly pressed contiguously arranged stiffening corrugations and provided with means constituting flanges angularly disposed with respect to the plane of said panel and projecting toward the interior of the car and means on the body of the car against which the bottom and vertical edges of the gate bear when in closed position.

13. In a drop end gondola car, the combination with the body of the car, of a sheet metal end gate hinged at its lower edge to the body of the car and consisting of a sheet metal end panel formed with a plurality of inwardly pressed contiguously arranged stiffening corrugations terminating within the edges of the sheet, the margin of said sheet being provided with means constituting flanges angularly disposed with respect to said sheet and projecting toward the interior of the car and means on the body of the car against which the bottom and vertical edges of the gate bear when in closed position.

14. In a drop end gondola car, the combination with the under frame, side walls and flooring of the car, of an angular member secured to the under frame, provided with an upstanding flange spaced away from said flooring, means on said side walls providing inwardly projecting flanges lying in the plane of said upwardly projecting flange, a

sheet metal corrugated end gate which consists of a metal sheet formed with a plurality of horizontally disposed corrugations terminating within the edges of the sheet and formed with a marginal stiffening rim projecting toward the interior of the car, and means for hinging said end gate to the car, comprising a U-bolt on said upstanding flange, a U-bolt on the bottom edge of said gate and a loop connecting said U-bolts.

15. In a drop end gondola car, the combination with the under frame and side walls of the car, of means constituting inwardly projecting flanges on the extremities of said side walls, an upwardly projecting flange on the under frame in the same plane with the aforementioned flanges, and a corrugated sheet metal end gate hinged at its lower edge to the car, provided with rigidifying members along its edges and adapted to bear against said flanges when in upright position.

16. In a drop end gondola car, the combination with the under frame and side walls of the car, of means constituting inwardly projecting flanges on the extremities of said side walls, an upwardly projecting flange on the under frame in the same plane with the aforementioned flanges, and a corrugated sheet metal end gate hinged at its lower edge to the car, provided with rigidifying members along its edges and adapted to bear against said flanges when in upright position, said corrugations lying within the space defined by said rigidifying members.

17. In a drop end gondola car, the combination with the under frame and side walls of the car, of means constituting inwardly projecting flanges on the extremities of said side walls, an upwardly projecting flange on the under frame in the same plane with the aforementioned flanges, and a corrugated sheet metal end gate hinged at its lower edge to the car provided with means constituting rigidifying flanges along its edges adapted to support the gate on the floor of the car, said gate being adapted to bear against the flanges on the side walls and under frame when in upright position.

18. In a drop end gondola car, the combination with the body of the car, of an end gate comprising a corrugated sheet metal panel provided with rigidifying members at its edges, means for hinging the lower edge of said gate to the car and means on the body of the car against which the edges of the panel bear when the gate is in closed position.

VINTON E. SISSON.
